UNITED STATES PATENT OFFICE.

ANDREW C. MOLHOLT, OF KENOSHA, WISCONSIN.

DESIGN FOR A WATCH-FOB, WATCH-CHARM, BROOCH, BREAST-PIN, OR SIMILAR ARTICLE.

51,210.

Specification for Design.

Patented Aug. 28, 1917.

Application filed July 5, 1917. Serial No. 178,879. Term of patent 14 years.

To all whom it may concern:

Be it known that I, ANDREW C. MOLHOLT, a subject of the King of Denmark, residing at Kenosha, in the county of Kenosha and State of Wisconsin, have invented a new, original, and ornamental Design for a Watch-Fob, Watch-Charm, Brooch, Breast-Pin, or Similar Article, of which the following is a specification, reference being had to the accompanying drawing, forming part thereof.

The figure is a face view of a watch fob, watch charm, brooch, breast-pin, or similar article, embodying my design.

I claim:

The ornamental design for a watch fob, watch charm, brooch, breast-pin or similar article as shown.

ANDREW C. MOLHOLT.
